STENCILS FOR DUPLICATING MACHINES

Archibald Joseph Parslow, Grange Park, England, assignor to Gestetner Limited, London, England, a British company

Application September 15, 1953, Serial No. 380,267

Claims priority, application Great Britain
September 18, 1952

2 Claims. (Cl. 101—128.2)

This invention relates to stencils for duplicating machines.

Stencils for duplicating machines are normally provided with a backing sheet which protects the stencil sheet before use and when cutting and which is removed when the stencil is put on the duplicating machine.

The object of this invention is to permit duplication of the information on the stencil in stages.

Another object is to enable a single stencil to reproduce two sets of copies of which both sets have certain information in common and one set has information additional to the other set.

A further object is to enable a single stencil bearing certain information to be used for reproducing two sets of copies bearing different information.

Yet a further object of this invention is the provision of a stencil bearing information in columns which permits certain of the columns only to be reproduced on one set of copies and all of the columns to be subsequently reproduced on another set of copies.

A practical application of the present invention will now be described, by way of example only, with reference to the accompanying drawings of which:

Figure 1 is a plan view of a stencil in accordance with the present invention looking on to the stencil sheet,

Figure 2 diagrammatically illustrates how the stencil of Figure 1 is used, and

Figures 3 is a view corresponding to Figure 1 showing an alternative construction of stencil in accordance with the present invention.

Referring to Figure 1: the stencil comprises a stencil sheet 5 and a backing sheet 6. The stencil sheet 5 is secured to the head 7 of the backing sheet in any well-known and convenient manner and the head 7 is adapted for attachment to the duplicating machine, for instance, it has holes 8 to engage pins on the machine.

The stencil sheet 5 is divided by a vertical, perforated line 9 (i. e. parallel with the long edge of the sheet) into two portions, which are generally indicated at 10 and 11. The portion 10 carries headings, as at 12, and is divided into columns, as at 13. Similarly, the portion 11 carries headings, as at 14, and is divided into columns, as at 15.

The backing sheet, as is customary, is horizontally divided from head 7 by a perforated line 16 so that the backing sheet may be removed from the head. Additionally, the backing sheet is divided into portions 17, 18 by a perforated vertical line 19 and it will be noted in Figure 2 that the perforations 9 and 19 are slightly offset across the width of the stencil for a purpose which will later be described. The portions 17 and 18 of the backing sheet correspond with the portions 10 and 11 respectively of the stencil sheet.

In use: the stencil is mounted on the duplicating machine (which is generally indicated in Figure 2 by the reference numeral 20) and thereafter the portion 17 of the backing sheet is removed by tearing along the perforations 16 and 19, for instance by holding the portion 17 as shown in Figure 2 and rotating the handle 21 of the

2

duplicating machine in the direction of the arrow a. Copies are then printed bearing only the information on the portion 10 of the stencil sheet 5, the portion 11 of the stencil sheet being covered by the portion 18 of the backing sheet so that this information is not reproduced. After a sufficient number of copies has been run off, the portion 18 of the backing sheet is removed and the required number of copies bearing the information on the entire stencil sheet is then run off. When using the copies so obtained, the copies with the information of the portion 10 only are sent externally of the organisation for which the copies are prepared, whereas the copies bearing this information and the additional information of the portion 11 are retained for use internally of the organisation.

Figure 3 illustrates a modified construction of stencil wherein the backing sheet is divided by a plurality of vertical lines of perforations 22 into a number of separately removable portions. It will be evident that the backing sheet may be provided with both horizontal and vertical lines of perforations, if so desired, i. e. the lines of perforations are parallel with both adjacent edges of the sheet.

The perforated line 9 will separate the information of portion 10 from that of portion 11 in the copies containing all the information of the stencil and also defines the extent of the last column of portion 10 in the copies containing only the information of the latter portion. By offsetting perforations 9 and 19 as shown in Figure 2 it is ensured that the perforated line 9 is reproduced on both sets of copies. Additionally, when producing the copies with restricted information ink penetrating line 9 does not pass on to the edge of portion 18 and smudge the copies.

I claim:

35 1. A stencil for use in a duplicating machine comprising a heading by which the stencil is attached to the machine, a stencil sheet permanently secured to the heading and a backing sheet removably secured to the heading, the backing sheet being of substantially the same dimensions as the stencil sheet and being sub-divided into at least two removable parts by a line of perforations extending between the heading and the backing sheet and at least another line of perforations extending fully across from one short edge of the backing sheet to another short edge and parallel to a long edge of the backing sheet.

40 2. A stencil for use in a duplicating machine comprising a heading by which the stencil is attached to the machine, a stencil sheet permanently secured to the heading and a backing sheet removably secured to the heading, the backing sheet being sub-divided into at least two removable parts by a line of perforations extending between the heading and the backing sheet and at least another line of perforations extending fully across from one short edge of the backing sheet to another short edge and parallel to a long edge of the backing sheet, and a 45 line of perforations on said stencil sheet parallel to said other line of perforations on the backing sheet but offset therefrom.

50 3. A stencil for use in a duplicating machine comprising a heading by which the stencil is attached to the machine, a stencil sheet permanently secured to the heading and a backing sheet removably secured to the heading, the backing sheet being sub-divided into at least two removable parts by a line of perforations extending between the heading and the backing sheet and at least another line of perforations extending fully across from one short edge of the backing sheet to another short edge and parallel to a long edge of the backing sheet, and a 55 line of perforations on said stencil sheet parallel to said other line of perforations on the backing sheet but offset therefrom.
